UNITED STATES PATENT OFFICE.

HOWARD I. MORRIS, OF CLEVELAND, OHIO, ASSIGNOR TO THE YODER-THOMAS MFG. CO., OF CLEVELAND, OHIO, A CORPORATION OF OHIO.

MAGNETIC OPERATING MECHANISM.

Application filed May 16, 1921. Serial No. 489,981.

To all whom it may concern:

Be it known that I, HOWARD I. MORRIS, a citizen of the United States, residing at Cleveland, in the county of Cuyahoga and

5 State of Ohio, have invented certain new and useful Improvements in and Relating to Magnetic Operating Mechanism, of which the following is a specification.

This invention relates to an automatically controlled valve mechanism, particularly of the thermostatic type, especially adapted to control the flow of a fluid, such as gas, through a conduit, whereby the use of the fluid may be economically controlled for 15 heating and other purposes.

One object of the invention is to provide a valve mechanism in which novel means are provided for controlling the valve.

Another object of the invention is to provide an improved valve operating mechanism capable of operating positively to seat and unseat the valve with a relatively quick action.

Another object of the invention is to provide an improved valve operating mechanism having a magnet which positively controls the valve.

Another object of the invention is to provide improved operating mechanism for a valve, whereby the fluid may be economically used and controlled.

A further object of the invention is to provide a positive valve operating mechanism of relatively few parts to insure durability, reduced cost of manufacture and quick operation of the valve.

Other objects of the invention will be apparent to those skilled in the art to which my invention relates from the following description taken in connection with the accompanying drawings.

For the purpose of illustration I have, in the accompanying drawings, shown and herein described one form of mechanism embodying my invention.

In the drawings, Figure 1 is an elevational view, partly broken away, illustrating a valve mechanism embodying my invention as applied to a water heating apparatus.

Fig. 2 is a longitudinal sectional view through the valve operating mechanism and the conduit through which the fluid to be controlled passes.

Fig. 3 is a section on the line 3—3 of Fig. 2.

Fig. 4 is an elevational view of one of the casing members.

Fig. 5 is a fragmentary view, similar to Fig. 2, but showing the position of the elements when the valve is closed.

Fig. 6 is a view similar to Fig. 5, showing the position of the parts when the valve is opened.

While I have illustrated in the drawings the application of my invention for use in connection with thermostatic elements which control the heating of water in a tank and maintaining it at any desired temperature, it will be understood that it is equally adapted for use where such elements control the heating of any other medium, such as air in a room or confined space.

1 indicates a tank adapted to contain water. 2 indicates a water supply pipe, which is connected to the tank in any suitable manner. 3 indicates a pipe leading from the tank to points where the heated water is desired for use. 4 indicates a burner having suitable jets. As shown in the drawings, the burner 4 is arranged below the tank 1, so that the water therein may be heated directly from the burner. When the burner is thus arranged, the tank is provided with a flue 5 through which the products of combustion escape, such arrangement being preferable as the flue extends through the tank and aids in quickly heating the water therein. The tank 1 may be mounted upon a standard 1^a or other suitable support.

2' indicates a pipe connected to the bottom of the tank 1, whereby it may be drained, when desired. The pipe 2' is provided with a suitable valve or cock as shown in the drawings. It will be understood that the pipe connections to and from the tank 1 may be arranged in any manner, other than that shown in the drawings, when desired.

6 indicates a conduit for the fluid, preferably gaseous fluid leading to the burner 4. 6^a indicates a valve which is preferably provided in the pipe 6 adjacent to the burner 4, whereby the flow of the gaseous fuel may be entirely cut off or regulated.

7 indicates a pilot arranged in juxtaposition to the burner 4 for well-known purposes. The pilot pipe 7^a preferably extends upwardly and is connected to the pipe 6 at a point above the valve and valve controlling mechanism to be later described. The pilot pipe 7^a is preferably provided with a valve 7^b.

8 indicates a casing which houses the valve 9 and the operating mechanism therefor, indicated as an entirety at 10. The casing 8 is interposed in and connected to the gas supply pipe 6, as will be later set forth. The casing 8 preferably comprises two members 11, 12, suitably shaped to facilitate their assembly for correlation with each other and assembly of the operating elements therein, as will later be apparent. The casing member 11 is provided with a curved seat or wall 13 to which the casing member 12 is secured in a well-known way, for example, by screws 14. The casing member 11 is formed with a chamber 15 which opens on its inner side through the wall 13. 16 indicates a plate of some suitable non-magnetic material, such as brass, which is preferably interposed between the casing members 11 and 12 and arranged to close the open end of the chamber 15, whereby escape of the gas from the conduit or chamber or into the casing member 12 is prevented. The plate 16 is relatively thin for purposes which will later appear.

17, 18, indicate a pair of hollow bosses provided on the upper and lower ends, respectively, of the casing member 11 and serving as connecting elements for the adjacent pipe ends 6^a, 6^b, of the pipe 6, these ends being screwed into the bosses in a well-known way.

19 indicates an opening formed in the casing member 11. The wall of the casing member 11 between the chamber 15 and opening 19 is formed with an inlet port 20 for the gas and the wall of the port is shaped and ground to provide a seat 21 for the valve 9. The open end of the opening 19 is provided with screw threads to receive a removable plug or cap 22. The cap 22 seals the opening 19. As shown, the opening is in line with the valve seat 21 and permits the assembly of the valve 9 and its replacement or repair, if that becomes necessary. 23 indicates a conduit formed in the casing member 11 and leading from the boss 17 to the chamber 19. 24 indicates a stem for the valve 9 depending therefrom into the chamber 15 for connection with and operation by the operating mechanism 10. I preferably provide the valve 9

with guides 9' which serve to maintain it substantially centrally of the seat 21 as it is opened and closed.

25 indicates a hollow boss provided on the casing member 12. The boss 25 is provided with external screw threads adapting it for connection with the walls of an opening 1^b formed in the side wall of the tank 1.

26, 27 indicate thermostatic elements extending into the tank 1. The element 26 preferably comprises a section of tubing formed from copper or other material capable of readily expanding under the influence of heat. The outer end of the element 26 is closed in any suitable manner. The inner end of the tube fits tightly within the boss 25 and is provided with a flange 26^a which engages a shoulder formed on the inner wall of the boss 25. 28 indicates a collar or ring member fitting within the boss 25 and against the shoulder to form a liquid tight joint to prevent leakage of the water in the tank 1 through the boss 25 into the casing member 12. The thermostatic element 27 is preferably formed from some material, such as porcelain, which is not to any substantial extent affected by temperature changes. The element 27 is arranged within the section of tubing 26 being connected at its outer end to the adjacent end of the tube 26 by any suitable device, such as a screw 29, which permits adjustment of the elements relative to each other when desired. The inner end of the thermostatic element 27 is, by preference, slidably mounted in the ring member 28 so as to be supported and guided at its inner end. The inner end of the element 27 is preferably provided with a cap 30, having a thrust element 31 extending axially from its outer face.

Since the inner end of the thermostatic element 26 is fixed to the casing 8 and its outer end is connected to the outer end of the thermostatic element 27, it will be understood that upon the rise in temperature of the medium surrounding the element 23, the latter expands and moves the element 27 endwise, or toward the left, as viewed in the drawings, and (2) when the temperature of the medium falls, the element 26 contracts and moves the element 27 endwise in the opposite direction, thereby serving to control the operation of the operating mechanism 10 as will be later set forth.

Of the operating mechanism 10, 32 indicates a lever pivoted upon a cross shaft or pivot 33 mounted at its opposite ends in suitable openings formed in the side walls of the casing member 12. 34 indicates a supplemental lever pivoted to the free end of the lever 32 and engaging a fulcrum 35 about which it rocks during movement of the lever 32. 36 indicates a magnet, preferably of the horse-shoe type, pivoted at or near its inner end upon a shaft or pivot pin 130

37, supported at its opposite ends in the walls of the casing member 12. 39 indicates a bar or rod connected to and extending across the gap between the two legs 38 of the magnet 36 and arranged to be engaged by the free end of the supplemental lever 34, to swing the magnet about its pivotal support 37. As shown in the drawings, the horse-shoe type of magnet provides a space 10 between its legs for the free end of the lever 32 to move in; and by bifurcating the free end of the lever 32, provision is made for the reception of the supplemental lever 34, whereby the lever 32, supplemental lever 34 15 and magnet 36 co-operate and move freely relative to each other in a relatively small confined space or chamber, so that compactness and reduced cost of manufacture are insured. The lever 32 is provided with an 20 abutment 32^a with which the thrust member 31 engages. When the thermostatic element 26 contracts due to fall in temperature of the water in the tank 1, it will move the thermostatic element 27 endwise toward the right, 25 as viewed in the drawings, and it in turn will act through the levers 32 and 34 to swing the magnet 36 about its pivot 37 upwardly. The operating elements just described are preferably arranged so that when 30 the water in the tank 1 is at the desired temperature, the magnet 36 is in a substantially horizontal position as shown in Fig. 2. 40 indicates a shaft extending transversely across the chamber 15 and secured at its opposite ends in the side walls thereof. 40' 35 indicates a rocker having a pair of wings 41, 41', of magnetic material extending to either side of the shaft 40. 42 indicates an arm fixed to the rocker 40' and pivotally 40 connected at its outer end to the lower end of the valve stem 24. As shown in the drawings, the free end or legs 38 of the magnet 36 are movable upwardly and downwardly relative to the shaft 40 to attract the 45 wings 41, 41', to rock the rocker 40' on its shaft 40 to open and close the valve 9.

From the foregoing description, it will be seen that the rocker 40' constitutes an armature pivoted intermediate its ends, 50 whereby movement of the magnet in opposite directions towards its ends will cause the armature to rock to either positively open or close the valve 9 with a relatively quick motion.

55 In operation—assuming that the water in the tank 1 is at the desired temperature—the elements of the valve operating mechanism 10 will be substantially in the position shown in Fig. 2 and the weight of the valve 60 9 and its stem, supplemented by the gas pressure will maintain it against its seat 21 and the wing 41 will be in its inner position and the wing 41' will be in its outer position. If the water in the tank 1 is allowed to cool or cooling takes place by rea-

son of the discharge of the hot water therefrom, the cooling effect will cause a contraction of the thermostatic element 26 and movement of the element 27 toward the right; such movement will in turn operate 70 the levers 32 and 34 and they in turn will swing the magnet 36 upwardly to the position shown in Fig. 6. As such movement of the magnet continues, it will overcome the weight of the valve stem and pressure of the gas on the valve and attract the armature 41', causing the rocker to rock about its pivot and open the valve with a relatively quick movement, as shown. Gas will now flow through the casing member 11 to the burner 4 and become ignited from the pilot 7; heating of the water will then take place. When the water has reached the desired, predetermined temperature, the heat thereof will cause the expansion of the tubing 26 and it will move the thermostatic element 27 endwise toward the left. As the thermostatic element 27 moves in this direction the levers 32, 34, will operate in the reverse direction, due to their weight and the weight 80 of the magnet 36, which will then move downwardly to the position shown in Fig. 5. As the magnet moves downwardly, it will move away from the armature 41' and toward the armature 41. As this movement 85 continues, the influence of the magnet 36 on the armature 41' gradually decreases, while its influence on the armature 41 gradually increases, so that after the magnet passes the shaft 40, the rocker will swing about its pivot with a relatively quick movement and close the valve 9, as shown in Fig. 5.

It will be seen that the magnet 36 is movable, and operates to both open and close the valve with relatively quick actions and these operations are effected by movement of the magnet relative to two armatures, which being connected together and mounted upon a common pivot are positively and alternately operated to open and close the valve by a single movement of the magnet relative to and to either side of the pivot about which the armatures swing.

The construction is particularly advantageous for the further reason that the magnetic influence between the magnet and one end of the rocker serves to maintain the valve in either position until it is positively moved to its other position; for example, in Fig. 5 the magnet 36 is shown at substantially its lowest position and attracting the armature end 41. Due to the magnetic influence upon the armature end 41, the latter will be maintained in that position (and the valve seated) while the magnet 36 is moving upwardly to the position shown in Fig. 6 until its influence on the armature end 41' exceeds its influence on the armature end 41, at which time there will 100 105 110 115 120 125 130

be a rapid decrease in the influence on the armature end 41 and a rapid increase in the influence on the armature end 41', the effect of which is to move the valve to the open 5 position quickly and positively.

From the foregoing description it will be seen that I have provided a relatively simple form of construction, consisting of few parts. Furthermore, it will be seen that I 10 have provided a construction in which the use of springs for operating or controlling any of the elements or parts or their relative movements are entirely eliminated.

It will also be seen that I have provided 15 two separate closed chambers in each of which are mounted certain of the valve operating elements, the armature or armatures being mounted in one chamber and the levers and magnet being mounted in another 20 chamber. I am therefore enabled to mount a minimum number of elements required for operating the valve 9 in the chamber through which the gas passes and to position all the remaining elements outside of that chamber. 25 This arrangement keeps the gas from flowing into the chamber containing the series of levers, thus preventing the accumulation thereon or the pivots therefor, of the elements, ingredients and compounds which 30 are contained in the gas. Furthermore, the plate 16 between the casing members 11 and 12 not only closes or seals the chamber 15, but maintains the magnet and armatures 41, 41', out of contact at all times, so 35 that they will not stick to each other.

Since magnetic attraction is relied upon to operate the armature 41, 41', (1) there is no connection between them and the means which control their movements; (2) 40 the valve is positively operated in each direction without the provision of a loose connection or a spring connection between any of its operating elements to insure quick or snap action; and (3) all packed joints, 45 glands and gaskets for openings for operating elements extending into the gas chambers or conduits of prior constructions are avoided.

The fulcrum 35 preferably comprises a 50 rod provided with screw threads which fit a screw-threaded opening in the lower portion of the casing member 12. This construction and arrangement permits the rod to be rotated and thereby adjusted endwise 55 so that the engagement of the supplemental lever 34 with the cross rod 39 can be controlled to regulate the operation of the magnet 36 relative to the armatures 41, 41', whereby the water in the tank 1 can be 60 maintained at a relatively higher or lower temperature, as desired.

To those skilled in the art of making 65 mechanisms of the class described, many alterations in construction and widely differing embodiments and applications of my

invention will suggest themselves, without departing from the spirit and scope thereof. My disclosures and the description herein are purely illustrative and are not intended to be in any sense limiting.

In this connection it will be noted that my construction is equally adapted for controlling the flow of materials through a conduit other than a fluid, such for example, as powdered or granular materials. It will 75 also be understood that the magnetic elements may be reversed so that the magnet will be connected to the valve and the armature moved relative to it.

What I claim is:

1. In apparatus of the class described, the combination of a thermostatic element, a conduit, a valve for said conduit, and a plurality of movable devices, one of which is magnetized and one of which forms an 85 armature, operatively connected to said thermostatic element and said valve, whereby by said thermostatic element moves one of said movable devices to effect opening and closing of said valve.

2. In apparatus of the class described, the combination of a thermostatic element, a conduit, a valve for said conduit, an armature connected to said valve, a magnet operatively connected to said element and pivoted to swing relative to said armature and through it to open and close said valve.

3. In apparatus of the class described, the combination of a conduit, a valve therefor, a pair of magnetic elements one of 100 which is connected to said valve and mounted to move about a pivot, and means for moving the other element relative to said first mentioned element.

4. In apparatus of the class described, the combination of a conduit, a valve therefor, a pair of magnetic elements one of which is connected to said valve and mounted to rock on a pivot arranged intermediate its ends, and means for moving the other element relative to said pivot towards the ends of said first mentioned element.

5. In apparatus of the class described, the combination of a conduit, a valve therefor, a pair of magnetic elements comprising a magnet and an armature, said armature being connected to said valve and mounted to move about a pivot, and means for moving the magnet relative to said armature.

6. In apparatus of the class described, the combination of a conduit, a valve therefor, an armature connected to said valve and mounted to rock on a pivot arranged intermediate its ends, a movably mounted magnet, and means for moving the said magnet relative to said pivot towards the ends of said armature.

7. In apparatus of the class described, the combination of a conduit, a valve therefor, an armature pivoted intermediate its ends

- and carrying an arm pivoted to said valve, and a magnet mounted to move in opposite directions toward the ends of said armature, and means for operating said magnet.
- 5 8. In apparatus of the class described, the combination of a conduit, a valve therefor, an armature pivoted intermediate its ends and carrying an arm pivoted to said valve, and a magnet mounted to move in opposite 70 directions toward the ends of said armature, and thermostatic means for operating said magnet.
- 10 9. In apparatus of the class described, the combination of a conduit, a valve in said conduit for controlling the flow of a fluid therethrough, a member mounted in said conduit and operatively connected to said valve for operating it, and means located entirely outside of said conduit for operating 80 said member.
- 15 10. In apparatus of the class described, the combination of a conduit, a valve in said conduit for controlling the flow of a fluid therethrough, and magnetic means for operating said valve, elements of said means being mounted in said conduit and other elements of said means being mounted outside of said conduit.
- 20 11. In apparatus of the class described, the combination of a conduit, a valve in said conduit for controlling the flow of a fluid therethrough, magnetic means for operating said valve, elements of said means being mounted in said conduit and other elements 90 of said means being mounted outside of said conduit, and thermostatic means for controlling said magnetic means.
- 25 12. In apparatus of the class described, the combination of a conduit, a valve in said conduit for controlling the flow of a fluid therethrough, a controlling member, an operating element connected to said valve, and an operating element operatively connected to said controlling member, and separated 95 from said first mentioned element, but constructed and arranged to transmit the power of said controlling member to operate said valve.
- 30 13. In apparatus of the class described, the combination of a conduit, a valve in said conduit, a controlling member, an operating element mounted in said conduit and connected to said valve, and an operating element operatively connected to said controlling member and arranged outside of said conduit, said elements being separated, but constructed and arranged to transmit the power of said controlling member to operate 100 said valve.
- 35 14. In apparatus of the class described, the combination of a conduit for a fluid, a casing interposed in said conduit and formed with a valved port and a closed chamber through which the fluid flows, a controlling member, an operating element mounted in 105 said closed chamber and connected to said valved port, and an operating element 110 connected to said controlling member and arranged outside of said closed chamber and connected to said valved port, and an operating element connected to said controlling member.
- 40 15. In apparatus of the class described, the combination of a conduit for a fluid, a casing having two separate chambers, one of which is connected to said conduit and formed with a valve for regulating flow of the fluid through it, a controlling member, and a pair of magnetic elements, one of said elements being mounted in said chamber connected to said conduit and operatively connected to said valve and the other element being in the other chamber and operatively 115 connected to said controlling member.
- 45 16. In apparatus of the class described, the combination of a conduit for a fluid, a casing having a closed chamber connected to said conduit and through which the fluid flows, and a separate chamber, a valve for controlling the flow of the fluid through said closed chamber, an operating element in said closed chamber and connected to said valve, a thermostatic element projecting into the separate chamber, and means in said separate chamber arranged to be actuated by said thermostatic element for operating the operating element in said closed chamber.
- 50 17. In apparatus of the class described, the combination of a conduit for a fluid, a casing having a closed chamber connected to said conduit and through which the fluid flows, and a separate chamber, a valve for controlling the flow of the fluid through said closed chamber, an armature in said closed chamber connected to said valve, a thermostatic element projecting into the separate chamber, and means in said separate chamber including a movable magnet arranged to be actuated by said thermostatic element for operating said armature in said closed chamber.
- 55 18. In apparatus of the class described, the combination of a conduit for a fluid, a casing having a closed gas chamber connected to said conduit and a separate chamber, a valve for controlling the flow of the fluid through said closed chamber, an armature pivoted intermediate its ends and connected to said valve, and an operating element mounted in 120 said closed chamber and connected to said valve.
- 60 19. In apparatus of the class described, the combination of a conduit for a fluid, a casing having a closed gas chamber connected to said conduit and a separate chamber, a valve for controlling the flow of the fluid through said closed chamber, an armature pivoted intermediate its ends and connected to said valve, and an operating element mounted in 125 said closed chamber and connected to said valve.
- 65 20. In apparatus of the class described, the combination of a conduit for a fluid, a casing interposed in said conduit and formed with a valved port and a closed chamber through which the fluid flows, a controlling member, an operating element mounted in 130 said closed chamber and connected to said valved port, and an operating element connected to said controlling member and arranged outside of said closed chamber and connected to said valved port, and an operating element connected to said controlling member.

- connected to said valve, a thermostatic element projecting into the separate chamber, and means in said separate chamber, arranged to be actuated by said thermostatic element for operating said armature in said closed chamber, said means including a magnet to be mounted to move in opposite directions toward the ends of the armature to alternately rock it on its pivot.
20. In apparatus of the class described, the combination of a gas conduit, a casing having a gas chamber connected to said conduit and through which the gas flows, and a separate chamber, a valve for controlling the flow of the gas through said gas chamber, and armature in said gas chamber connected to said valve and mounted on a pivot arranged intermediate its ends, a thermostatic element projecting into the separate chamber, means in said separate chamber arranged to be actuated by said thermostatic element for operating said armature, said means including a magnet movable in opposite directions towards the ends of said armature for alternately rocking it on its pivot, whereby said valve is opened and closed, and a relatively thin wall of non-magnetic material arranged between said magnet and said armature.
21. In apparatus of the class described, the combination of a thermostatic element, a conduit, a valve for said conduit, a plurality of elements, one of which is magnetized and one of which forms an armature, operatively connected to said thermostatic element and said valve and controlled by said thermostatic element to open and close said valve, and a relatively thin wall of non-magnetic material arranged between said magnetized element and said armature.
22. In apparatus of the class described, the combination of a conduit, a valve in said conduit, an armature pivoted intermediate its ends and connected to said valve, and a magnet movable from end to end of said
- armature and serving to hold one end of the armature in attracted position until its influence upon the other end overcomes the attraction upon the first mentioned end, whereby the armature is operated with a relatively quick movement.
23. In apparatus of the class described, the combination of a movable member, a movably mounted armature connected to said member for operating it, a horseshoe magnet pivoted at its inner ends and arranged so that its free ends move relative to said armature, a lever having its free end extending to and movable between the legs of said magnet, a supplemental lever pivotally connected to the free end of the first mentioned lever and engaging said magnet to move it, a fulcrum on which said supplemental lever moves, and means for engaging and operating said first mentioned lever.
24. An apparatus as claimed in claim 22, in which a thermostat element is operatively connected with and moves said magnet.
25. In apparatus of the class described, the combination of a controlling member, a conduit, a valve for said conduit, a pair of armatures arranged to move simultaneously in opposite directions, connections between said armatures and said valve, and a movably mounted magnet operatively connected to and moved by said controlling member relative to said armatures to effect operation thereof.
26. An apparatus as claimed in claim 1, in which that device operatively connected to the valve is mounted to rock about a pivot due to the magnetic influence set up between it and the device operatively connected to and moved by said thermostatic element.
- In testimony whereof I affix my signature.
- HOWARD I. MORRIS.
